Primary Examiner — Marianne Pandozzi*(74) Attorney, Agent, or Firm* — Gary J. Foose**CLAIM**

The ornamental design for a dispensing cup, as shown and described.

DESCRIPTION

FIG. 1 is a perspective view of a dispensing cup showing my new design;

FIG. 2 is a side view of the dispensing cup of FIG. 1;
FIG. 3 is a rear view of the dispensing cup of FIG. 1;
FIG. 4 is a side view of the dispensing cup of FIG. 1, opposite the side view shown in FIG. 2;
FIG. 5 is a front view of the dispensing cup of FIG. 1;
FIG. 6 is a top view of the dispensing cup of FIG. 1; and
FIG. 7 is a bottom view of the dispensing cup of FIG. 1.
The broken lines in the drawing depict portions of the dispensing cup that form no part of the claimed design.**1 Claim, 1 Drawing Sheet**(56)
